UNITED STATES PATENT OFFICE.

FRANCIS M. ROSENFELD, OF NEW YORK, N. Y., ASSIGNOR, BY MESNE ASSIGNMENTS, TO DIAMOND ELECTRIC SPECIALTIES CORP., OF NEWARK, NEW JERSEY, A CORPORATION OF NEW JERSEY.

PORTABLE LAMP.

1,355,849.

Specification of Letters Patent. Patented Oct. 19, 1920.

Application filed February 5, 1919. Serial No. 275,155.

To all whom it may concern:

Be it known that I, FRANCIS M. ROSENFELD, a citizen of the United States, and a resident of the city, county, and State of 5 New York, have invented an Improvement in Portable Lamps, of which the following is a specification.

The present invention relates to an improvement in portable lamps, one object 10 being to provide a device of this character in which the lighting circuit may be conducted through an exterior portion of the casing while another exterior portion effectively insulated to prevent accidental 15 closing of the circuit by the interposing of a conductor between said portions. It is also contemplated that the present improvements will be instrumental in simplifying the construction of devices to which they 20 may be applied.

An embodiment of my invention is illustrated in the drawings forming a part of the present specification and in which,

Figure 1 is an elevation, 25 Fig. 2, a central vertical section, Fig. 3, a bottom plan view of the reflector and lamp assembly, and

Fig. 4, a detail view partly in section showing a modification where the casing is 30 non-conductive and the switch includes a slidable contact rod engaging the contact plate directly.

As shown in the drawings, a device embodying my invention may include a casing 35 1 of any suitable material either a conductor or a non-conductor. At one end of the casing 1, a cap 2 may be attached by any suitable means, here shown as a threaded portion engaging a similarly threaded portion 40 of the casing. Said cap is preferably provided with a spring member 3 adapted to bear against a battery 4 having one pole at 5 and the other pole at 6. At the end of the casing opposite cap 2 is another similarly 45 attached cap 7 provided with an opening adapted to receive and retain a lens or other light transmitting member 8.

Between the lens 8 and the battery 4, I provide lamp supporting means and means 50 adapted to facilitate contact between one pole of the lamp and pole 6 of the battery. I also provide means for establishing contact between the opposite pole of the lamp and pole 5 of the battery. For this purpose,

a metallic strip 9 is provided and positioned 55 so that one end thereof may be electrically connected with a portion of cap 2 which in turn is in current conducting relation to pole 6 of the battery through the spring 3. A terminal 10 on strip 9 is positioned to co- 60 operate with a suitable switch, illustrated in the drawings as including terminals 11 and 12 adapted to be moved into contact with terminal 10 on said strip 9.

In the present case, a reflector 13 of any 65 suitable material may be interposed between the lens 8 and the casing 1. Said reflector being preferably provided with projections 14 at its lower end surrounding an opening 15 adapted to permit the passage of the 70 nipple 16 of a lamp 17. The nipple 16 may be supported in a socket 18 attached to or forming a part of a contact plate 19 provided with projecting portions 20. Between the reflector 13 and the socket 18, I provide 75 an insulating member 21 having perforations adapted to receive the projections 14 of the reflector and having other perforations adapted to receive the projections 20 of the contact member. The free ends of 80 said projections are bent against the adjacent surface of said insulating member, thus securing both the reflector 13 and the contact plate 19 to the insulating member 21.

In operation, the battery 4 is inserted in 85 the casing 1 with pole 5 in contact with one pole of the lamp 17. Current is transmitted to the other pole of the lamp through contact 6, spring 3, cap 2 and any suitable switch mechanism such as the one herein 90 above described. It will be readily understood that the strip 9 may be fixed as in Fig. 2, or slidable as in Fig. 4, depending on the character of the switch. In any event, strip 9 will be in current contacting 95 relation with contact member 19 when the circuit is complete.

The foregoing construction is intended to effectively insulate the lamp socket in such a way that no current will pass through the metallic reflector. In portable lamps, it has been found that a metallic tool interposed between the metallic caps of the lamp very often completes the circuit and burns out the battery to no purpose. By insulating 100 the reflector through which the current has ordinarily been transmitted heretofore, this undesirable result is avoided.

I claim as my invention:

1. In a portable electric light, the combination of a casing, a battery within the casing, a lamp in circuit with said battery through a conductive portion of the casing, a reflector, a contact member, insulating means arranged between said reflector and said contact member and having spaced perforations, means projecting from the reflector and passing through said perforations in the insulating means to fasten said reflector and insulating means together, and means for fastening the contact member to the insulator.
- 15 2. In a portable electric light, the combination of a casing, a battery within the casing, a lamp in circuit with said battery

through a conductive portion of the casing, a reflector, a contact member, insulating means between said reflector and said contact member and having two sets of spaced perforations, means projecting from the reflector and passing through one set of spaced perforations in the insulating means to fasten said reflector and insulating means together, and means projecting from the contact member and passing through the other set of spaced perforations in the insulating means to fasten said contact member to said insulating means.

In testimony whereof, I have signed my name to this specification this 31st day of January, 1919.

FRANCIS M. ROSENFIELD.
